UNITED STATES PATENT OFFICE.

ELIE GAUCHER, OF CONSTANTINOPLE, TURKEY.

AIR-COMPRESSOR OR VACUUM-PUMP.

No. 895,084.

Specification of Letters Patent.

Patented Aug. 4, 1908.

Application filed March 11, 1907. Serial No. 361,765.

To all whom it may concern:

Be it known that I, ELIE GAUCHER, a citizen of the Republic of France, residing at Constantinople, in Turkey, have invented a 5 certain new and useful Improved Air-Compressor or Vacuum-Pump, of which the following is a specification.

This invention relates to a pump for compressing air and producing vacuum; the said 10 apparatus compresses air by means of oil, all its parts work in the latter fluid by which they are automatically lubricated, and it does not require any attendance.

In the accompanying drawing given merely 15 by way of example, Figure 1 is a sectional longitudinal elevation of the apparatus. Fig. 2 is a horizontal cross-section of the apparatus on the line A B of Fig. 1.

In the said drawing, 10 is a tank filled with 20 oil less the volume generated by the travel of the piston. The upper wall 11 of the said tank 10 is inclined and connects the left-hand lateral wall of the said tank 10 to the left-hand lateral wall of a part 12 arranged at 25 a higher level. The cylinder 13 which is closed at the top by a cover 14 provided with holes, opens at the bottom into the tank 10.

The piston 15 is constructed of two parts, the bottom one of which is convex so as to 30 prevent any air remaining below it at the moment when the chamber 10 is filled with oil, which is done when the piston is at the bottom portion of its stroke. Moreover, the said piston 15 is provided with two stamped 35 out leathers held between the two parts constituting the piston which parts are mounted on the rod 16 passing through the cover 14 with little friction. The inlet valve 17 can slide in the part 18 which forms the seat and 40 guide. The conduit 19 is connected by screwing at the bottom to the seat-guide 18 and opens at the top into the upper portion of the cylinder 13. The discharge valve 20 is arranged in the interior of the seat 21, and 45 its rod is guided in the part 22 screwed to the part 21. A pipe 23 is screwed into the part 22 and opens at its upper end bent downwardly into a chamber 24. The portion of the pipe 23 within the chamber 24, is closed 50 at the end, and provided at the sides with small holes 25. It will be readily understood that in this way any oil carried away, cannot escape through the upper portion of the chamber 24, and reach the air tank, as it is 55 projected against the walls of the chamber, to the bottom of which it descends.

The chamber 24 is provided with a removable bottom 26 and with a branch 27 by means of which it is connected to a chamber 28 provided with a removable cover 29. The 60 chamber 28 is of suitable dimensions to enable the pivot pin 31 for one of the ends of the lever 32, provided with a valve 33, to be mounted in it with ease. The pin 31 is held at the upper end of a screw plug 34, and the 65 seat of the valve 33 is formed by the upper end of a second hollow screw-plug 35. The other end of the lever 32 is connected in a suitable manner to a float 36 contained in the chamber 24. The plug 35 is connected 70 by a pipe 37 to an orifice 38 in the cylinder 13.

It will be readily understood that when the oil in the chamber 24 has reached a certain level the float 36 and also the valve 33 are raised and then the oil contained in the 75 chamber constituted by 24 27 and 28, will flow into the cylinder 13 until the float 36 and the valve 33 have returned to their position of rest.

In order that the float 36 be not deformed 80 by the pressure of air, it may be packed inside with cork.

40 is a tube to indicate the level of the oil in the chamber 24: if it were to break the cocks 42 and 43 would have to be at once 85 closed.

A pipe 44 establishes a constant communication between the upper portions of the chamber 24 and of the chamber 28.

After having placed the float 36 in the 90 chamber 24 and mounted the lever 32, the chamber 24 and the chamber 28 are closed by putting on and bolting the bottom 26 and the cover 29. Then the cocks 42, 43 and 45 are opened, the plug 46 of the cover 29 is removed in order to put oil into the chamber constituted by 28, 27 and 24 until the liquid has reached the float 36, whereupon the cock 45 is closed, and the plug 46 put back into place.

100 A check valve 47 is arranged between the chamber 24 and the branched pipe 48 which is provided with two cocks 49 and 50 connecting the compressor to the compressed-air tank.

The chamber 51 has for its object to receive the oil which owing to high compression may pass between the walls of the cylinder 13 and the piston 15. As soon as there is an excess of oil on the upper face 15, the said oil escapes into the chamber 51 through the opening 52, raises the float valve 110

53 and is drawn into the inlet pipe through the orifice 54: the said chamber 51 is open at its upper portion.

In order to fill the tank 10 the screw-threaded cap 55 is withdrawn, the piston 15 lowered to the bottom of the cylinder 13 so as to expel any air from under the piston. Oil is then introduced through the nozzle 56, the air escaping through the said nozzle. 10 The tank having been filled, the piston rod is connected to the connecting rod of the driving engine, the piston is raised to the top of the stroke, and while it is in that position, oil is poured on its upper portion in order to 15 fill the top of the cylinder 13 up to the orifice 52 through which the excess of oil will escape on to the inlet valve 17, following the pipe 19 or passing through the chamber 51 and raising the float 53 in the said chamber. 20 In that case the oil escapes through the pipe 60 and rises again through the pipe 61. This arrangement is specially useful when the apparatus is utilized for producing vacuum in which case the cock 58 is closed while the 25 cock 57 is opened. In these conditions, in spite of the cock 58 being closed, the oil carried away returns to the tank 10. Then the piston 13 is lowered to the bottom of its stroke and it is ascertained through the orifice of the nozzle 56 whether the oil does not 30 rise up to the latter. If not, then more oil is poured in, until it overflows, and then the screw-threaded cap 55 is replaced.

If it is merely desired to have compressed 35 air, the cock 57 is closed, and the cock 58 opened. The suction takes place at the top of the cylinder 13 through the orifice 52. The compressed air will be forced into the tank through one of the cocks 49 or 50, the 40 one not used being closed.

If it is desired both to produce a vacuum and to compress, the cock 58 is closed, the pipe 62 of the cock 57 connected to the tank in which vacuum is to be produced and the 45 said cock 57 is opened.

The oil carried away by the air discharged, is collected by the chamber 24, and when the oil reaches a certain level, it will raise the float 36 flow to the upper portion of the 50 cylinder 13 and thence into the pipe 19 above the valve 17, so that when the latter is lifted off its seat owing to the suction of the piston 13, the oil comes in first, and the air afterwards. In that way the oil is automatically 55 returned into the tank 10 in which no clearance is ever formed.

It must be pointed out that all the parts of this apparatus subject to friction, are always lubricated by the oil which is constantly 60 circulating.

What I claim as my invention and desire to secure by Letters Patent is:—

1. A combined air compressor and vacuum pump comprising in combination, a tank 65 filled with oil or the like, a cylinder com-

municating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a float controlled oil by-pass connecting said suction pipe between said cylinder and cock and between said cock and said suction valve, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

2. A combined air compressor and vacuum pump comprising in combination, a tank filled with oil or the like, a cylinder communicating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

3. A combined air compressor and vacuum pump comprising in combination, a tank filled with oil or the like, a cylinder communicating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

4. A combined air compressor and vacuum pump comprising in combination, a tank filled with oil or the like, a cylinder communicating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

5. A combined air compressor and vacuum pump comprising in combination, a tank filled with oil or the like, a cylinder communicating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

6. A combined air compressor and vacuum pump comprising in combination, a tank filled with oil or the like, a cylinder communicating with said tank at its lower end and provided with an air inlet at its upper end, a driven piston for said cylinder at all times engaging the oil in said tank on its lower end and being covered with oil on its upper end, a suction pipe connecting the upper end of said cylinder with the upper portion of said tank, a suction valve at the tank terminal of said pipe, a cock for said suction pipe located between said terminal valve and said cylinder, a vacuum extension for said suction pipe provided with a cock and adapted for connection with a vacuum tank, a discharge pipe connected with said oil tank and provided with a discharge valve at its tank terminal, a float chamber partially filled with oil and connected with the other terminal of said discharge pipe, a pipe connecting said float chamber with the upper end of said cylinder and adapted to provide a supply of oil to the upper end of said piston, a valve for the chamber terminal of said pipe, a float in said chamber controlling said valve, and a compressed air pipe leading from said float chamber and provided with a non-return valve.

at all time, a suction pipe connecting the upper end of said cylinder with the upper portion of said tank, a suction valve at the tank terminal of said pipe, a discharge pipe 5 connected with said tank and provided with a discharge valve at its tank terminal, a float chamber partially filled with oil and connected with the other terminal of said discharge pipe, a pipe connecting said float chamber with the upper end of said cylinder 10 to maintain a supply of oil on the upper end of said piston, a valve for the chamber terminal of said pipe, a float in said chamber controlling said valve, and a compressed air 15 pipe leading from said float chamber and provided with a non-return valve.

4. An air compressor comprising in combination, a tank filled with oil or the like, a cylinder communicating with said tank at 20 its lower end and provided with an air inlet at its upper end, a driven piston for said cylinder engaged by the oil of said tank at all times, a suction pipe connecting the upper end of said cylinder with the upper portion 25 of said tank, a suction valve for the tank terminal of said pipe, a discharge pipe connected with said tank and provided with a discharge valve at its tank terminal, a chamber partially filled with oil and connected 30 with said discharge pipe and the upper end of said cylinder, means disposed in said chamber for controlling the supply of oil therein to said cylinder, and a compressed air pipe leading from said chamber and provided with a non-return valve.

5. A combined air compressor and vacuum pump comprising in combination, a tank filled with oil or the like, a cylinder opening 35 into said tank at its lower end and provided with an air inlet at its upper end, a driven piston for said cylinder engaged on its lower end at all times by the oil from said tank, a

suction pipe provided with a valve and a cock and connecting the upper portion of said tank with the upper portion of said cylinder, a vacuum extension pipe connected with said suction pipe and provided with a cock, a discharge pipe connected with said tank and provided with a valve, a chamber partially filled with oil and connected with 45 said discharge pipe and the upper end of said cylinder, means disposed in said chamber for controlling the supply of oil therein to the upper end of said piston, and a compressed air pipe leading from said chamber. 50

6. An air compressor comprising in combination, a tank filled with oil or the like, a cylinder communicating with said tank, a driven piston for said cylinder engaged by the oil of said tank, a suction pipe connecting 60 the upper end of said cylinder with said tank, a discharge pipe connected with said tank, a chamber partially filled with oil and connected with said discharge pipe and having a separate connection with the upper end of 65 said cylinder, a compressed air pipe connected with said chamber, and means disposed in said chamber for controlling the supply of oil therein to said cylinder.

7. An air compressor comprising in combination, a tank partly filled with oil or the like, a cylinder communicating with said tank, a piston for said cylinder engaged by the oil of said tank on one of its faces, means for covering the other face of said piston with 70 oil and means for carrying off an excess of oil from said other face of said piston. 75

In testimony whereof I have affixed my signature, in presence of two subscribing witnesses.

ELIE GAUCHER.
